FRED B. RICE, OF DOVER, MASSACHUSETTS, ASSIGNOR TO RICE & HUTCHINS, INCORPORATED, OF PORTLAND, MAINE, A CORPORATION OF MAINE.

DISPLAY-FORM FOR BOOTS AND SHOES.

1,172,736.

Specification of Letters Patent.

Patented Feb. 22, 1916.

Application filed October 27, 1915. Serial No. 58,281.

To all whom it may concern:

Be it known that I, FRED B. RICE, a citizen of the United States, and resident of Dover, county of Norfolk, State of Massachusetts, have invented an Improvement in Display-Forms for Boots and Shoes, of which the following description, in connection with the accompanying drawings, is a specification, like letters on the drawings representing like parts.

My present invention relates to a shoe or shoe form having a transparent portion. Such transparent portion will permit a view of a foot or foot model as it is actually held in the shoe form. Preferably the transparent portion will not prevent the entire shoe form from being bent or flexed to simulate the action of a shoe during walking.

The object of the present invention is to enable the position of the human foot in a shoe to be displayed and studied either while at rest or during the movement incident to walking. To this end I provide a shoe having a transparent portion which is so located, or is itself sufficiently flexible, as to permit the shoe to be bent or flexed as it is during walking. I may also place a flexible model of a foot within the shoe, and bend both the shoe and model, to display the movement of the foot within a shoe. Such a model may be of rubber or other flexible material, or of course, the transparent shoe form may be fitted directly upon the human foot and displayed in this manner. In the action of walking, the forepart of the foot is necessarily moved on the insole and within the shoe upper, as the foot is bent backwardly and forwardly, flexing the sole and shoe across the forepart. By having the upper transparent, the actual relative movement of the foot, particularly the forepart and toes within the shoe, will be displayed. In narrow toed shoes the malignant effects of crowding the toes together, during walking especially is clearly displayed, while in a broad toed or "common sense" shoe the natural position and movement of the foot permitted, at rest or during walking, is also displayed. Cutting away a portion of the shoe, of course, entirely removes the confining effects of the shoe and therefore would not permit an accurate display or observation of the position of the foot, nor the action of a foot,

while confined within a shoe to be seen. I believe that it is a distinct novelty in this art to provide a shoe with a transparent portion, particularly such a transparent portion through which to observe the action of the foot or a flexible model of a foot while bending the shoe.

Referring to the drawings: Figure 1 is a view of my shoe form having a transparent upper; Fig. 2 is a side view of a shoe having transparent portions only at toe and heel, illustrating the model of a foot within a shoe; Fig. 3 is a view similar to Fig. 2, showing the model foot and shoe when flexed, simulating walking, with the forepart and toes of the model in their forward position; and Fig. 4 is a plan view of the shoe form and model shown in Fig. 2, with the position at the toes of the model as illustrated in Fig. 3 shown in dotted lines. Fig. 5 is a view illustrating a shoe with a transparent portion; Figs. 6 and 7 are corresponding views of the shoe shown in Fig. 5, corresponding to Figs. 3 and 4, illustrating a foot model and its action during walking visible within the transparent portion of the shoe.

I may utilize any suitable form, style, or make of shoe, preferably of well known construction, the shoe illustrated in the drawings being of the well known "Educator" style, with broad "common sense" toes and of child's size. Such a shoe has the usual outsole 1 and insole 2, united by stitching, or in any desired manner, and a transparent upper 3 having its edge portions fastened over the insole 2 and engaged between the insole 2 and outsole 1. This transparent upper 3 may be of any suitable material, and preferably it is so located or is flexible to permit the sole and insole to be bent and flexed to simulate the walking action. I prefer to utilize celluloid or a specially treated textile fabric which will be sufficiently transparent and at the same time flexible, but an upper with a large number of perforations, such as a wire mesh or screen might also be employed. The essential features of the transparent portion of the display form are that it will permit the position or the movement of walking of the foot within the shoe to be observed, while, at the same time, confining the foot or model as closely as a leather

upper would confine it, and preferably of sufficient form or flexibility to permit the sole and boot model to be bent.

As the transparency of the forepart or 5 vamped of the shoe upper is most desirable, to my present display form, I may simply make the forepart transparent, and unite it with a leather, canvas, or textile upper, or as shown in Fig. 2, make the display 10 form simply with a transparent vamped 4, fitting within the shoe the rubber model or mold of a foot 5, then flexing or bending the insole and model and displaying the 15 relative movement of that portion of the model within the transparent vamped 4 while confined therein. In order to retain the model 5, as well as to complete the appearance of the display form illustrated in Figs. 2 and 3, I prefer to add a counter or heel 20 part 6 which may be also transparent, as illustrated in the drawings, or which may be of leather, cardboard, or the like. As illustrated in Figs. 3 and 4, when the shoe and model are bent backwardly and forwardly, simulating walking, the forepart and toes of the model move relatively with the shoe, forwardly approximately into the position as shown in Fig. 3, and as indicated in dotted lines in Fig. 4. The more 25 the foot and shoe are bent, the further are the toes crowded into the forepart, as well known.

In Figs. 5, 6 and 7 I have illustrated a modification utilizing a transparent portion 30 in a shoe. The transparent portion may be attached to the remaining portion of the shoe upper, or not, as desired, but constitutes a foot-retaining inclosure through 35 which the model 5 and its action during 40 walking can be seen. In this form the transparent portion 10 may be united to the upper or vamped 11 by adhesive or other means, or may simply overlap or underlap the adjacent portions of the vamped 11 and 45 a slight sliding, during flexing of the model and shoe, will result without injury to either. In a shoe of this type the foot-retaining and confining effect is more accurately reproduced than where a transparent 50 section only is utilized, as in the form shown in Figs. 1 to 4. My invention contemplates, broadly, the use of any transparent section in a shoe, or transparent portion 55 alone, such transparency carrying out the normal contour of the shoe, retaining or confining the foot within said contour and still permitting a view of the foot, or a foot model, within.

My display form therefore permits an accurate and careful display and study of the 60 action of a foot in a shoe particularly during walking, while the foot is actually confined by the shoe upper. This is a result, of course, which could not be obtained by the 65 prior display apparatus, wherein the shoe

part itself is entirely removed as the foot or model is then not confined. While I have illustrated the display form in an "Educator" type of shoe, I contemplate in actual use, the employment of a variety of styles 70 of shoe forms with transparent uppers, showing, variously, the effects of the foot in walking while the toes are too much confined, as in a pointed toed shoe, or too much expanded, as in too wide a shoe, as well as in 75 the proper form and style which preserves the foot from distortion while permitting a full and free movement. I contemplate utilizing my transparent shoe form as an educational display apparatus, using a pointed 80 toed model with a transparent portion to illustrate the confining and crowding of the toes and foot, together with a similar sized but different style shoe form, having a corresponding transparent portion to illustrate 85 the unconfining action of this style. Also to use similar comparative shoe forms with the transparent portion or structure so arranged as to permit the flexing of the sole and model as in walking. As above explained, this result can be secured either by having the transparent portion as a small section only of the shoe, as near the toe portion, or as the edge of the upper around the sole and only of sufficient height to insure 90 the foot confining action, while these constructions also permit a flexing of the form when desired.

Having described my invention, what I claim as new and desire to secure by Letters 100 Patent is:

1. A display form for boots and shoes having a transparent foot-inclosing portion to confine the foot or foot model therein, while permitting a view of the same there- 105 through.

2. A display form for boots and shoes, comprising a transparent upper portion, in combination with a foot model therein, said transparent portion permitting a view there- 110 through of the foot model confined therein.

3. A display form for boots and shoes, having a transparent flexible foot-inclosing portion to confine the foot or foot model, while permitting a view of the same during 115 flexing of the display form.

4. A display form for boots and shoes, having a transparent flexible upper to confine a foot or foot model, while permitting a view of the same during flexing of the display form. 120

5. A display form for boots and shoes, comprising a shoe with a transparent upper portion, and a flexible foot model therein, both shoe and model being capable of movement simulating walking, while permitting a view of the foot model through the transparent portion. 125

6. A display form for boots and shoes, comprising a shoe of leather, canvas, or the 130

like, having incorporated in the structure of the shoe a transparent section permitting a view to the interior of the shoe, while preserving the normal shoe contour.

5 7. A display form for boots and shoes, comprising a shoe of leather, canvas, or the like, having a portion of the leather and lining removed, and a flexible, transparent material substituted for said removed portion, permitting a view to the interior of the shoe.

10 8. A display form for boots and shoes, comprising a shoe of leather, canvas, or the like, having a portion of the upper removed

and transparent, flexible material substituted therefor, said transparent material constituting a foot-confining means for the transparent section substantially equivalent to the foot-confining effect of the leather for which said transparent material is substituted. 15
